ACOUSTIC DEVICE

Filed Sept. 22, 1921

Inventor:
Charles L. Goodrum,
by Joel Ch. Palmer
Atty.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

ACOUSTIC DEVICE.

Application filed September 22, 1921. Serial No. 502,425.

This invention relates to acoustic devices. One of the objects of the invention is the provision of a very light and stiff acoustic diaphragm.

5 This invention relates to acoustic devices and more particularly to diaphragms for use in such devices.

The object of the invention in general is to provide a light relatively stiff diaphragm, the movement of which in response to vibrations will be approximately the same at any point on its surface thereby simulating that of a piston.

In order to obtain a diaphragm in which 15 the movement throughout the whole area will be approximately equal in response to sound vibrations, or in the production of such vibrations, it has heretofore been the practice to make them relatively thick at the center 20 portion and gradually tapering toward the peripheral portion. Such diaphragms are usually constructed by co-axially superimposing a plurality of layers of material of different diameters. The improved results 25 thus obtained, as compared with a simple diaphragm of uniform thickness due to increased stiffness, is offset, to some extent at least, by the increased weight.

In accordance with the general features of 30 this invention there is provided a hollow diaphragm so constructed that use may be made of very light material. In its preferred form the diaphragm consists of two 35 dished surfaces, formed of a light and comparatively stiff material and secured together to form a hollow body having a double convex surface, the opposing sections serving to mutually reenforce and stiffen each other in the direction of the applied 40 vibration.

The accompanying drawing is a perspective view, partly in cross section, of a talking machine sound box in which are incorporated both features of the invention.

45 The acoustic diaphragm is here shown in its preferred form, which comprises two similar dished members 1 which are preferably made of very thin woven fabric, such as linen, impregnated with a phenolic condensation product, pressed into the form shown, and hardened by the application of heat and pressure. A spacer 2 of very light material, such as cork, is inserted between the members 1, and is clamped in place by 55 the small bolt 3. After the diaphragm is

assembled its outer surfaces are varnished and it is again subjected to heat treatment.

The peripheral portions of the diaphragm are preferably secured together as shown. The diaphragm is shown mounted between a pair of pneumatic tubes 4, but any other suitable means may be employed. Such a diaphragm is obviously of very light weight as compared with a solid structure of equal dimensions, and the members 1, although 65 they are very thin, are capable of withstanding considerable lateral stress without appreciable distortion, due to the dished formation. A movement of the diaphragm in response to sound vibrations in the important audible range, or in the production of sound vibrations in the important audible range, simulates very closely the movement of the piston. The effect of the added stiffness due to the particular shape used is to 70 shift the lowest resonant frequency to the higher parts of the audio range of frequencies where the damping is normally much greater, thereby reducing tone distortion to a minimum.

80 The stylus bar 5 is attached to the bolt 3 and is thereby capable of transmitting to the diaphragm the vibrations imparted to the stylus 6 by the record 7. The stylus bar 5 is pivoted on the knife edge 8, which is carried by the sound box member 9, and is provided with a pair of adjusting screws 10, which bear against the resilient cushions 11, 85 preferably of rubber, which in the present instance are shown as spherical in shape.

90 Although the invention as illustrated is applied to a reproducer, it is understood that it is equally applicable to all acoustic devices employing diaphragms.

What is claimed is:

1. A hollow acoustic diaphragm comprising two initially dished members and a spacer of fixed length therebetween disposed at the center portions of said members.

2. A hollow acoustic diaphragm comprising two initially dished members secured together at their peripheral portions and separated at their center portions thereby forming a closed chamber.

3. A hollow acoustic diaphragm comprising two initially dished members secured together at their peripheral portions and separated a constant distance at their center portions, and a spacer of fixed length disposed between said members.

4. A diaphragm for an acoustical device comprising a pair of initially dished members secured together at their peripheries with their hollow sides facing each other, and forming a closed rigid structure capable of vibrating as a unit.
5. As an article of manufacture, a diaphragm construction for reproducers consisting of two similarly formed conical diaphragms outwardly flanged at their peripheries and secured together to provide an enclosed compartment therebetween without sound openings therein.
6. As an article of manufacture, a diaphragm for sound reproducers consisting of two circular members of sheet material having central depressions therein and juxtaposed with their peripheral portions in contact and their central portions separated, and means supported by said members for securing them together to form a closed hollow acoustic chamber.
7. As an article of manufacture, a diaphragm for sound reproducers consisting of two circular members having depressed central portions juxtaposed with their peripheral portions in contact, a separator between the central portions and means extending through said members and said separator to secure said members together to form a closed hollow chamber.
8. As an article of manufacture, a diaphragm for sound reproducers consisting of two conical members, means independent of any diaphragm mounting, for securing said members together with their peripheral portions in contact and their apices separated to form a closed hollow chamber.
9. As an article of manufacture, a dia-
- phragm for sound reproducers consisting of two conical members juxtaposed with their peripheral portions in contact and their apices separated and facing in opposite directions, and means through the center of said members for securing them together to form a closed hollow chamber.
10. As an article of manufacture, a diaphragm for sound reproducers consisting of two sheets of thin and inherently stiff material having central depressions therein juxtaposed with their depressed portions facing in opposite directions and separated and their peripheral portions in contact, and means holding said sheets in said relation to form a closed hollow chamber, said means forming a part of said diaphragm.
11. As an article of manufacture, a diaphragm for sound reproducers comprising two conical members of sheet material outwardly flanged at their peripheries and juxtaposed with their flanges together to form a closed hollow acoustic chamber, and means forming a part of said diaphragm for holding said members together.
12. As an article of manufacture a diaphragm consisting of two sheets of thin material in conical form, said sheets being juxtaposed with their peripheral portions together to mutually reinforce each other and form a closed hollow chamber, and means for holding said members in said relation, said means being part of said diaphragm.

In witness whereof, I hereunto subscribe my name this 20th day of September, A. D. 75
1921.

CHARLES L. GOODRUM.
